UNITED STATES PATENT OFFICE.

IRWIN FLOYD KEPLER, OF AKRON, OHIO, ASSIGNOR TO THE B. F. GOODRICH COMPANY, OF SAME PLACE.

DESIGN FOR A BATHING-CAP.

SPECIFICATION forming part of Design No. 34,196, dated March 5, 1901.

Application filed January 28, 1901. Serial No. 45,145. Term of patent 14 years.

To all whom it may concern:

Be it known that I, IRWIN FLOYD KEPLER, a citizen of the United States, residing at Akron, in the county of Summit and State of Ohio, have invented and produced a new, useful, and original Design for a Shape or Configuration of Bathing-Cap, of which the following is a specification, reference being had to the accompanying drawings, forming part thereof.

Figure 1 is a side view, and Fig. 2 a top view, of a bathing-cap, showing its shape and configuration. Fig. 3 is a sectional view taken on the line $x-x$ of Fig. 1.

As shown in the drawings, the leading or material features of my design consist of a head-opening (marked A) and an enlarged pouch, (marked B,) the said pouch being domical, similar in shape to a Russo-Byzantine cupola,

as shown in Fig. 1, having the series of sector-like sections c radiating from the center and alternating with a series of radially-extending ribs, grooves, or corrugations d , disposed or arranged as shown in Fig. 2, the said sections c being convex in cross-section and the ribs d being concave, as shown in Fig. 3.

Having described my invention, what I claim as new, and desire to secure by Letters Patent, is—

The design for a bathing-cap as herein shown and described.

In testimony whereof I have signed my name to this specification in the presence of two subscribing witnesses.

IRWIN FLOYD KEPLER.
